(57) **CLAIM**

The ornamental design for a bracelet, as shown and described.

DESCRIPTION

1. Bracelet
- 1.1 : Perspective
- 1.2 : Front
- 1.3 : Back
- 1.4 : Right
- 1.5 : Left
- 1.6 : Top
- 1.7 : Bottom
- 1.8 : Open perspective

The bracelet comprises two semi-elliptical elements articulated at one of their ends, their other ends connected by a clasp comprising a pivoting locking element held by one of the said other ends; the locking element comprising an essentially parallelepiped-shaped plate with chamfered corners, holding two unlocking buttons and having a keyhole.
